G. HAMMOND,
MAGAZINE CATCH AND RELEASE FOR FIREARMS,
APPLICATION FILED FEB. 28, 1918.

Patented Feb. 15, 1921.

INVENTOR,
Grant Hammond.
BY
Arthur B. Jenkins.
ATTORNEY.

UNITED STATES PATENT OFFICE.

GRANT HAMMOND, OF NEW HAVEN, CONNECTICUT, ASSIGNOR OF ONE-THIRD TO ALVA C. WASHBURNE, OF PITTSFIELD, MASSACHUSETTS, AND ONE-THIRD TO FREDERICK G. CRANE, OF DALTON, MASSACHUSETTS.

MAGAZINE CATCH AND RELEASE FOR FIREARMS.

1,368,719.

Specification of Letters Patent. Patented Feb. 15, 1921.

Application filed February 28, 1918. Serial No. 219,589.

To all whom it may concern:

Be it known that I, GRANT HAMMOND, a citizen of the United States, residing at New Haven, in the county of New Haven 5 and State of Connecticut, have invented a new and Improved Magazine Catch and Release for Firearms, of which the following is a specification.

My invention relates more especially to 10 magazines used in firearms now commonly known as "automatic," that is, one in which the extracting of the shell and the loading of the firearm is accomplished by the automatic action thereof, and an object of my 15 invention, among others, is to provide a magazine with the use of which the rapidity of firing may be increased by providing for the automatic release and ejection of the empty magazine; and a further object of 20 the invention is to provide a magazine that shall be comparatively inexpensive in its structure so that it may be discarded after having been once used and without involving much loss.

25 A firearm constructed to receive a magazine embodying one form of my invention is illustrated and described herein, in which—

Figure 1 is a view in side elevation of a 30 firearm embodying my invention, with parts broken away to show construction.

Fig. 2 is a view in section through the same on plane denoted by dotted line 2—2 of Fig. 1.

35 Fig. 3 is a detail bottom view of the receiver constructed to receive my improved magazine.

Fig. 4 is a side view of my improved 40 magazine with parts broken away to show construction.

Fig. 5 is a detail view of the case that contains the releasing rod.

Fig. 6 is an end view of the same.

Fig. 7 is a view in cross section through 45 the handle on plane denoted by dotted line 7—7 of Fig. 1.

Fig. 8 is a view in cross section through the handle on plane denoted by dotted line 50 8—8 of Fig. 1, the magazine being removed.

55 In the accompanying drawings the numeral 10 indicates the handle, comprising a portion of the frame, 11 the trigger guard,

12 the trigger, 13 the barrel, 14 the receiver, 15 the hammer and 16 the breech-bolt of a 55 firearm, all of which parts may be constructed in any desired manner and of proper material. A breech-bolt stop 17 is movably mounted in the side of the receiver to engage a shoulder 18 on the breech-bolt 16 and hold it in its rearward position when 60 the magazine is not in its proper place in the handle, the magazine being constructed so that its end 19 will engage the stop and hold it in its inoperative position when the 65 magazine is in its proper position. The 70 construction and operation of the parts above described will be readily understood by those skilled in the art and a further description is, therefore, omitted herein, it being sufficient simply to state that when the magazine is moved from the position shown in the drawings the stop 17 will be forced by its spring into position to intercept forward movement of the breech-bolt.

A magazine releasing rod is movably 75 mounted with respect to the magazine to effect the release of said magazine, this rod preferably being mounted on the handle, and in the structure herein shown a releasing rod case 20 is secured to the side of the 80 handle 10, preferably as by means of a plate 21 formed integral with the case, which plate is secured to the side of the handle in any desired manner. The case and plate are preferably formed of a single piece of sheet 85 metal bent to shape, this piece of sheet metal being formed and cut to provide a flap that is bent preferably into round form to constitute a spring case 22, and as shown in 90 Figs. 5 and 6 of the drawings.

A releasing rod 23 is inclosed within the case 20 for sliding movement lengthwise 95 therein. This rod is constructed preferably from a piece of sheet metal and with a shoulder 24 to receive a releasing rod actuating spring 25 that is seated at one end against this shoulder and at its other end against an overturned lip 26 at the end of the spring case 22. A hook 27 is formed at one end of the releasing rod to engage a 100 releasing rod holder 28. In the preferred form of construction this holder comprises a shoulder in the side edge of a slot 29 extending downwardly from the upper end

of a magazine 30, the part of the slot below this shoulder constituting a releasing notch 31. The lower end of the releasing rod comprises a magazine catch release, in the form 5 of construction herein shown, this release being formed as a cam 32 to engage a nose 33 on the end of a catch lever 34, preferably mounted on the side of the handle and as shown in Fig. 1 of the drawings. One end 10 of this lever is formed into a thumb piece 35 that projects to the outer surface of one of the grip pieces 36, and a lug comprising a magazine catch 37 is formed on the under side of this lever to engage a hole 38 in the 15 side of the magazine to hold the latter in place.

The end of the releasing rod is of such resiliency that it may be forced from engagement with the holder 28, and it is so 20 positioned that as the follower 39 in the magazine moves upwardly it will engage the end of the rod or hook 27 and thrust it off from the holder 28. In the structure herein shown a releasing cam 40 is formed 25 on the side of the follower to operate the hook 27 and disengage it from the holder 28.

It will be seen from the drawings in connection with the above description that in the successive feeding movements of the 30 cartridges into the barrel, the follower will travel upwardly under the force of its spring 41 in a manner that will be readily understood. When the last cartridge 44 in the magazine is forced into the barrel by the 35 forward movement of the breech-bolt, the follower will be moved by its spring against the bottom of the breech-bolt, and in this position the cam 40 will be in close proximity to the hook 27.

40 At the next firing action, caused by the hammer 15 when released by the trigger 12, the breech-bolt will be forced backwardly by the exploding gases beyond the follower, releasing the latter that will be 45 forced upwardly until stopped by lips 42 at the mouth of the magazine. In this final upward movement of the follower the cam 40 will engage the hook 27 and release it from the holder 28, upon which release the 50 spring 25 will move the rod 23 quickly downward, causing the cam 32 to engage the nose 33 of the catch lever 34 and move the catch lug 37 from within the hole 38. The magazine being thus released will drop from 55 its chamber within the handle, in which movement the breech-bolt stop 17 will be released and moved into the path of the breech-bolt which it will catch and hold in its backward position. It will be understood 60 that this entire action takes place very quickly and in the time between the release of the follower by the breech-bolt and the completion of the backward movement of the breech-bolt.

65 When the next magazine, with a cartridge

or cartridges therein, is manually forced to place in the handle, the lips 42 on the magazine will engage the stop 17 releasing it from the breech-bolt and the latter will move forward under the force of its spring 70 carrying with it the uppermost cartridge in the magazine and forcing it into the barrel. In this inward movement of the magazine the holder 28 thereon will engage the hook 27 and move the releasing rod 23 upwardly 75 and from engagement with the catch lever, whereupon the latter will be moved by its spring to engage the catch 37 with the magazine to hold it in place.

In accordance with the provisions of the 80 patent statutes, I have described the principles of operation of my invention, together with the device which I now consider to represent the best embodiment thereof; but I desire to have it understood 85 that the device shown is only illustrative, and that the invention may be carried out by other means.

I claim:—

1. A firearm including a frame having a 90 magazine chamber therein, a magazine insertible in said chamber, means to retain the magazine in place, a releasing member adapted to be engaged with said retaining means to operate it, means to operate the 95 releasing member to release said retaining means, and means adapted to be engaged with said releasing means and controlled by the feeding movement of cartridges into the barrel to effect operation of the releasing 100 member to operate the retaining means to release the magazine.

2. A firearm including a frame having a magazine chamber therein, a magazine insertible in said chamber and provided with 105 a follower, means to retain the magazine in place, a releasing member adapted to be engaged with said retaining means to operate it, said releasing member being adapted to be engaged with said follower to effect the 110 actuation of said retaining means to release the magazine, and means to operate the releasing member to disengage it from said retaining means after it has been engaged therewith.

3. A firearm including a frame having a 115 magazine chamber therein, a magazine insertible in said chamber, a magazine catch to retain the magazine in place, a releasing rod adapted to be engaged with said retaining means to operate said catch, means to operate the rod to release the catch, and means adapted to be engaged with said rod and controlled by the feeding movement of cartridges into the barrel to effect operation of the rod to operate the catch to release the magazine.

4. A firearm including a frame having a magazine chamber therein, a magazine insertible in said chamber, a magazine catch 130

to retain the magazine in place, a releasing rod to operate said catch, said rod being formed and positioned for engagement with a follower in the magazine, and a follower 5 to engage said rod to permit its operation to actuate the catch to release the magazine.

5. A firearm including a frame having a magazine chamber therein, a magazine insertible in said chamber, a magazine catch to 10 retain the magazine in place, a releasing rod to operate said catch, means operated by insertion of the magazine into the frame to operate the rod to release it from said catch after it has been engaged therewith 15 and to retain said rod in its released position, and means controlled by the feeding movement of cartridges into the barrel to release said rod and permit operation thereof to actuate the catch to release the magazine. 20

6. A firearm including a frame having a magazine chamber therein, a magazine insertible in said chamber, a magazine catch to retain the magazine in place, a releasing rod 25 to operate said catch, means operable by reason of movement of the magazine into its chamber to engage said rod and move it to release it from the catch and to hold it in this position, and means controlled 30 by the feeding movement of cartridges into the barrel to effect operation of the rod to operate the catch to release the magazine.

7. A firearm including a frame having a magazine chamber therein, a magazine insertible in said chamber and having a holder, 35 a magazine catch to retain the magazine in place, a releasing rod mounted on the frame and formed to engage the holder on the magazine for operation of the rod for release from the catch by movement of the magazine into its chamber, and means controlled 40 by feeding movement of cartridges into the barrel to effect operation of the rod to operate the catch to release the magazine. 45

8. A firearm including a frame having a magazine chamber therein, a magazine insertible in said chamber and having a shoulder, a releasing rod movably mounted on 50 the frame and having its end formed to engage said shoulder and to be located in the path of movement of a follower in the magazine, and a follower located in the magazine to engage said rod to release it from 55 said shoulder to permit its movement to actuate the catch to release the magazine.

9. A firearm including a frame having a magazine chamber therein, a magazine insertible in said chamber and having a slot 60 formed with a shoulder, a follower located in the magazine and having a cam surface, a releasing rod movably mounted on the frame and having its end formed to engage said shoulder and said cam on the follower,

and a catch movably mounted on the frame 65 in the path of movement of the releasing rod.

10. A firearm including a frame having a magazine chamber therein, a magazine insertible in said chamber, a releasing rod movably mounted on the frame, and having means located in the path of movement of the magazine into the frame to effect movement of said rod in one direction, means for moving the rod in the opposite direction, 75 said rod having a cam surface on its end, and a magazine catch movably mounted on the frame in the path of movement of said cam surface.

11. A firearm including a frame having a magazine chamber therein, a magazine insertible in said chamber, a case secured outside of the frame, a releasing rod slidable in said case, the end of said rod being formed to engage the magazine and to be engaged 80 by the follower therein, means for moving the rod within the case, and a magazine catch located opposite the lower end of the case and in the path of movement of the rod 85 therein. 90

12. A firearm including a frame having a magazine chamber therein, a magazine insertible in said chamber, a case formed of a single piece of metal and secured to the outer side of said frame, said case also comprising 95 a spring case, a shouldered releasing rod located in the case, a spring located in the spring case and seated against said shoulder, the end of the releasing rod being formed for engagement by the magazine and the 100 follower therein, a follower located in the magazine, and a catch located in the path of movement of said releasing rod.

13. A firearm including a frame having a magazine chamber therein, a magazine insertible in said chamber, a case formed of a single piece of metal and secured to the outer side of said frame, said case being of trough 105 shape, a fastening plate bent outwardly from the edge thereof, and a spring case bent 110 into round form from one edge of the trough shaped part and at the end of the plate, a shouldered releasing rod located in the case, a spring located in the spring case and seated against the shoulder on said rod, 115 means on the end of the rod to engage a follower in the magazine, a follower located in the magazine, and a catch located in the path of movement of said releasing rod.

14. A case for the magazine releasing rod 120 of a firearm, said case being of trough shape, a fastening plate bent outwardly from the edge of a side part of the case, and a spring case bent inwardly into tubular form from said edge of the case. 125

15. A magazine for a firearm comprising a case with a slot in one side thereof, a holding shoulder formed within said slot that is

open from said shoulder to the end of the case, said shoulder forming a bottom of said opening, and a releasing notch at the bottom of said slot.

5 16. A magazine for a firearm comprising a case with a follower therein, said case having a slot in the side thereof, a holding shoul-

der within said slot that is open from said shoulder to the end of the case, said shoulder forming a bottom of said opening, the bottom of the slot comprising a releasing notch, and a releasing cam on said follower. ¹⁰

GRANT HAMMOND.
